FIG.1

FIG.2

Julius Greenstein
INVENTOR.

BY *Lawrence L. Colbert*
ATTORNEY

UNITED STATES PATENT OFFICE

139,095

DESIGN FOR A CALENDAR BASE OR SIMILAR ARTICLE

Julius Greenstein, New York, N. Y.

Application August 7, 1944, Serial No. 114,758

Term of patent 3½ years

(Cl. D74—5)

To all whom it may concern:

Be it known that I, Julius Greenstein, a citizen of the United States of America, residing in the Borough of Bronx, city of New York, county of Bronx, and State of New York, have invented a new, original, and ornamental Design for a Calendar Base or Similar Article, of which the following is a specification, reference being had to the accompanying drawing, forming part thereof.

Figure 1 is a top perspective view of a calendar base or similar article, showing my new design; and

Figure 2 is a top plan view, thereof.

I claim:

The ornamental design for a calendar base or similar article, as shown.

JULIUS GREENSTEIN.
